UNITED STATES PATENT OFFICE.

RAYMOND R. RUNDELL, OF ELMIRA, NEW YORK, ASSIGNOR OF ONE-HALF TO VERNE A. HOLLOWBECK, OF HAMMONDSPORT, NEW YORK.

SHADE-HOLDER.

1,370,671.

Specification of Letters Patent.

Patented Mar. 8, 1921.

Application filed August 20, 1919. Serial No. 318,751.

To all whom it may concern:

Be it known that I, RAYMOND R. RUNDELL, a citizen of the United States, residing at Elmira, in the county of Chemung and State of New York, have invented certain new and useful Improvements in Shade-Holders, of which the following is a specification.

My invention relates to improvements in holders for lamp shades and the like, and particularly to elements of the holder for securing the shade in position so that excessive vibration such as is produced on street cars, or other moving bodies, will not unlock the shade from the holder.

An object of my invention is to provide a holder of the character above indicated of a minimum number of parts capable of being easily and cheaply manufactured, and adapted for a quick and secure assemblage with the shade which it is to support.

Further objects and advantages of the details of the invention will appear from the description in connection with the accompanying drawings to be hereinafter set forth.

The invention consists of structural characteristics and relative arrangements of elements which will be hereinafter more fully described and particularly pointed out in the appended claims.

In the drawings, in which similar reference characters indicate the same parts in the several figures:—

Figure 1 is an elevation view, partly broken away, of a shade holder embodying my invention;

Fig. 2 is a plan view, partly in section, taken on line II—II of Fig. 1;

Fig. 3 is a detail sectional view of part of the holder showing the holding means in a position to permit the placing of a shade in position, or removal thereof, and

Fig. 4 is a section on line IV—IV of Fig. 2.

In the drawings 10, is the holder adapted to be mounted preferably by means of threads 10' and in the usual manner. The holder 10 is provided on its depending section with a plurality of apertures 11 through 50 which balls 12, of any suitable material, as

fiber or hard rubber, may project. The balls 12 are of larger diameter than the apertures 11, so they cannot pass or fall through them, but when they are pressed against the apertures they project through 55 sufficiently, as indicated in Figs. 1 and 2, to engage a shade S, for which the holder 10 is designed and securely hold it in place. In Fig. 3, the ball does not project through the aperture 11 so far and it permits the shade 60 S, to be put in position, in the holder or removed from it.

In order to render the balls 12 operative for holding a shade in the holder, a channeled sleeve 13 having openings 14 therein 65 is rotatably mounted upon the depending section of the holder 10 and rests upon a flange 15 of the holder. The openings 14 of the sleeve 13 correspond in number and relative position to the apertures 11 in the 70 holder and are of sufficient size at one end to permit the balls 12 to pass through; from this large portion of the opening it is gradually tapered to the other end. The sleeve 13 is provided with a slot 13' in its 75 lower edge as shown in Fig. 2, for purposes of permitting the holder to be assembled as will be hereinafter explained and is corrugated along the edges of each of the openings 14 near the small end of it, as shown at 80 15', in order to securely lock the balls in place, as will hereinafter be set forth.

To assemble the holder, a spring 16 is placed in the sleeve 13, after which the sleeve 13 having its slot 13' registering with the 85 lug 17, is dropped over the holder and turned until said spring 16 has been compressed between lugs 17 and 18, which have been struck out from the holder and in from the sleeve respectively. When the spring 16 has 90 been sufficiently compressed as to bring the large ends of openings 14 in the sleeve 13, coincident with the apertures 11 in the holder 10, the balls 12 may be inserted, after which the sleeve may be released and the 95 spring will automatically actuate the elements constituting the holder to the position shown in Fig. 2.

The last operation in the construction of the holder is to punch out a lip or projec- 100

tion 19, in the holder 10 which engages in a slot 20 in the rotatable sleeve 13 to provide a limit of travel for the sleeve so that the large part of the opening 14, cannot be brought back in line with the apertures 11 and permit the balls to fall out and also prevents the sleeve 13, from becoming separated or disassembled from the holder.

The operation of the device is as follows:

- 10 The normal position of the parts is as shown in Figs. 1 and 2 of the drawing. In order to position a shade S, in a holder or remove it therefrom, it is necessary to partially turn or rotate the sleeve 13 in a clockwise direction against the pressure of the spring 16, thereby permitting the balls 12 to have more freedom in the openings 14 of the sleeve, so they can be retracted sufficiently from the apertures 11 in the holder to permit the insertion of the shade, as indicated in Fig. 3, a portion of the shade S, being shown in broken lines. Upon inserting the shade S, and releasing the sleeve 13, the spring 16, will actuate the sleeve in a counter-clockwise direction positioning a narrower part of the openings 14, over the balls 12, and forcing them into engagement with the shade S, and securely locking it in place. The corrugations 15', along the edge of the sleeve 13, are provided, if desired, and tend to force the balls to exert a greater pressure on the shade S, than the spring 16 would normally produce and also lock the same in position, so that excessive vibration will not affect the holder in the least.

It will be seen from the foregoing disclosure that I have provided a particularly simple and adaptable construction for the purposes set forth and of such form and size as to be utilized with any standard form of lamp or shade holders without in any way affecting the usual appearance or design adopted by the many manufacturers of this class of devices.

- 45 In the drawings there is indicated a holder employing three sets of apertures 11 and coöoperating balls 12, and one spring 16, however any desired number of apertures and balls could be employed as well as an increased number of springs if desired. It is obvious that various changes may be made without departing from the essential features and principle of my invention, and I do not wish to be understood as limiting myself to the specific and preferred construction herein shown and described, or that the invention could only be applied to holders for lamp shades.

What I claim is:

- 60 1. A lamp shade carrier comprising an annular holder having apertures therethrough, balls adapted to project through said apertures, and a movable sleeve mounted on the outer side of said holder adapted to position said balls against said holder

within its apertures by the movement of said sleeve to engage a lamp shade.

2. A lamp shade carrier comprising an annular holder, a plurality of balls carried by said holder adapted to extend inwardly 70 from the holder, and means rotatable on the outer side of said holder for forcing said balls inwardly to engage a lamp shade.

3. A lamp shade carrier comprising a holder, elements carried by said holder 75 adapted to extend inwardly therefrom for coupling a lamp shade inserted within said holder, and means comprising a sleeve carried by and rotatable on the outer side of the holder so constructed, arranged and adapted to force said elements into engagement with the lamp shade by rotation of said sleeve.

4. A lamp shade carrier comprising a holder, movable elements carried by the holder adapted to extend inwardly therefrom, and a movable sleeve carried by and on the outer side of said holder so constructed, arranged and adapted to force said movable elements inwardly to engage a lamp shade.

5. A lamp shade carrier comprising a holder, movable elements carried by the holder adapted to extend inwardly therefrom, a movable sleeve carried by and on the outer side of said holder, means between 95 the holder and sleeve for causing the sleeve to normally engage said movable elements and force them inwardly to engage a lamp shade.

6. A lamp shade carrier comprising an 100 annular holder provided with a plurality of openings, a sleeve provided with a plurality of openings and movably supported on the outer side of said holder, balls loosely supported within the openings of said holder and sleeve, said openings in said holder and sleeve constructed and arranged to retain the balls on the holder and permit them to readily move from or toward the center of the annular holder.

7. A device of the character described comprising a holder, elements carried by the holder adapted to extend inwardly therefrom, a rotatable sleeve carried by said holder, openings in said sleeve through 115 which said elements project, means for forcing said elements inwardly by rotating said sleeve.

8. A device of the character described comprising a holder, movable and independent elements carried by the holder adapted to extend inwardly therefrom, a sleeve carried by and rotatable on said holder, said sleeve having tapered openings through which said elements are adapted to 125 project and so constructed and arranged that by rotating said sleeve in one direction the tapered edge of the openings will force said elements inwardly to engage a body inserted within the holder.

9. In the device set forth in claim 8, means comprising corrugations in the sleeve along the edge of the tapered opening for rigidly locking the elements carried by the holder in their inner position.

10. In the device set forth in claim 8, means comprising a spring mounted be-

tween the holder and sleeve for rotating the sleeve to force the elements inwardly.

11. In the device set forth in claim 8, means for limiting the distance said sleeve can be rotated.

In testimony whereof I affix my signature.
RAYMOND R. RUNDELL.
